H. KALLIS.

CRANK AND LEVER MECHANISM FOR WINDMILLS.

APPLICATION FILED JAN. 9, 1914.

1,154,404.

Patented Sept. 21, 1915.

UNITED STATES PATENT OFFICE.

HENRY KALLIS, OF WESSINGTON SPRINGS, SOUTH DAKOTA.

CRANK AND LEVER MECHANISM FOR WINDMILLS.

1,154,404.

Specification of Letters Patent. Patented Sept. 21, 1915.

Application filed January 9, 1914. Serial No. 811,172.

To all whom it may concern:

Be it known that I, HENRY KALLIS, a citizen of the United States, and a resident of Wessington Springs, in the county of Jerauld and State of South Dakota, have made certain new and useful Improvements in Crank and Lever Mechanism for Windmills, of which the following is a specification.

My present invention relates to windmills and more particularly to certain improvements relating both to the means directly through which the power is developed and also to the means associated therewith for directing and controlling the application of such power to the practical use for which structures of this character are generally intended.

A further object of my invention is to provide a simple and novel means by which the developed power may be divided and transmitted to a plurality of transmission devices and subsequently adapted to a plurality of uses, either of the same or different characteristics.

With these and other objects in mind, and which will be made more apparent from the following description, my invention resides in the several structures shown in the accompanying drawing, forming a part of this specification and in which the figure is a sectional side elevation through my improved windmill.

Referring now to the figure, I have shown in the lower portion thereof three pumps A, A' and A² to be operated. Above these pumps rises the structural framework of the windmill, indicated generally at B and including an upper rigid platform B' and an intermediate similar rigid platform B², the former of which supports, preferably upon rollers b, the usual rotating platform C, and the latter of which has a central opening and an apertured supporting cup b' upon its lower surface which receives the lower ends of inner and outer guide tubes D and D' respectively. The outer guide tube D' has a threaded connection at its lower end in the cup b' and a similar threaded connection at its upper end within a centrally flanged aperture of the rotating platform C, and the inner guide tube D is disposed therein and is adjustable by means of set screws d so that it may be centered and thus effectually guide the several transmission tubes which are mounted therethrough in telescoping relation to rotate and

move longitudinally. As will be seen, there are three of these transmission tubes respectively indicated at E, E' and E², the central tube E being connected to the rod of pump A' by means of a connecting frame a, the arms of which are connected at their upper ends to a yoke a' loosely surrounding the lower portion of the tube, a nut a² being threaded upon the lower extremity of the tube so that when the latter is moved upwardly the pump rod will be moved forwardly therewith, the weight of the latter serving to lower it when the tube is lowered.

The lower end of the intermediate transmission tube E' depends below the lower end of the outer tube E² and is terminated a corresponding distance above the lower end of the inner tube E. Around the lower end of the tube E' just mentioned is loosely disposed a yoke f and a nut f' is threaded on the tube below the yoke, the yoke being carried by the inner ends of levers F, the outer ends of which are fulcrumed upon the lower portion of a bracket f² secured to and depending from one side of the intermediate stationary platform B². Upon the lower end of the outer transmission tube E² is similarly disposed a yoke f², this yoke being above a nut f⁴ and being carried by the inner ends of levers F', the outer ends of which are fulcrumed upon the lower end of a bracket f⁵ depending from the relatively opposite side of the platform B² as compared to bracket f² before mentioned. The levers F and F' are provided with a series of intermediate apertures f⁶ and f⁷ respectively, through selected ones of which pins f⁸ may be extended, these pins receiving the upper ends of connecting arms F² and F³ respectively, connecting the levers F and F' with the rods of pumps A and A².

Secured upon the upper rotating platform C is a frame G consisting of uprights and an upper cross bar G', the latter of which forms a bearing for the upper ends of connecting arms e, e' and e² secured at their lower ends to the upper ends of the respective transmission tubes E, E' and E², the upper ends of the intermediate and outer tubes E' and E² being cut away in order to obviate interference with one another during their longitudinal movement. Adjacent its lower end the frame G is provided with horizontal bearings for the usual wind wheel shaft H upon one end of which is secured the wind wheel H' and upon the opposite end

of which is secured a brake-disk H^2 , this shaft being provided with three intermediate cranks h , h' and h^2 , preferably set at 120 degrees with respect to one another and respectively connected to the connecting arms e , e' and e^2 of the transmission tubes by means of upwardly inclined pitmen h^3 , h^4 and h^5 . Thus when the wind wheel is rotated the shaft H being correspondingly moved transmits its power through the several pitmen to the several crank arms and thus power is in turn communicated to the several transmission tubes and from these tubes to the several pumps through the means previously described.

In operation, the wind wheel is held in the wind by means of a vane I projecting from the relatively opposite side of the platform C , the inner portion of this vane being journaled upon an upright pivot shaft I' having connection at its lower end with the platform C and having its upper end supported by one end of a horizontal arm J intermediate secured to the frame G . The vane I is normally held in operative position by a spring I^2 coiled about the pivot shaft I' and may be moved to an inoperative position as shown in dotted lines in Fig. 4 by means of a flexible connection K secured at one end to the vane and guided over pulleys k and having connection at its opposite end to the lower arm of a bell crank lever K' , the other arm of which is connected to the upper end of a controlling rod K^2 which depends through the inner transmission tube E and has its lower end terminated at a point substantially therebelow in order to be within easy reach of the operator. On one face of the vane I are a plurality of ribs i , which, when the vane is moved to inoperative position, come into contact with the brake-disk H^2 and serve to check the wind wheel shaft H . This action is produced by a downward pull upon the lower end of the controlling rod K^2 which draws the vane I away from the position shown and in which it is normally held by the spring I^2 before mentioned, to the inoperative position. It is apparent that when this is done and the wind wheel no longer held in the face of the wind, the contact with the several ribs i against the brake-disk H^2 will effectually serve the purpose for which these parts are intended. It is evident that by the use of the several structures I have set forth and described in detail, the power developing parts may be readily moved into and out of

operation and when in operation the power so developed may be transmitted through the several transmission tubes and to the several uses such as mentioned. It should be noted, however, that the application of the power through the means described is not limited to the actuation of pumps but may be employed for various other purposes as desired. It should also be noted that various changes may be made in so far as either the details of the power developing or transmitting parts are concerned without varying the result which is obtained thereby and without departing from the spirit of my invention as outlined in the appended claims.

I claim:

1. In a structure of the character described the combination of a plurality of cranks, a rotating platform upon which the said cranks are mounted, inner and outer guide tubes depending from the said platform and the outer one of which is stationarily held at its upper and lower ends, adjusting screws working through the outer guide tube and against the inner guide tube whereby to center the latter, a plurality of telescoping transmission tubes depending through the guide tubes and independently movable, connections between the upper ends of said transmission tubes and the cranks, and connections at the lower ends of the said transmission tubes whereby their movement may be independently utilized.

2. In a structure of the character described, the combination of a plurality of cranks, telescoping transmission tubes depending below the said cranks, said tubes being independently connected at their upper ends to the said cranks and having their lower ends terminated in stepped relation, guides through which the tubes are mounted to independently move, a support which carries the guides, levers fulcrumed at their outer ends to the support adjacent the lower ends of certain of the transmission tubes, yokes loosely surrounding the lower ends of the said tubes and to which the inner ends of the levers are connected, and connecting arms having adjustable connections intermediate the ends of the said levers whereby the movements of the said tubes may be independently utilized.

HENRY KALLIS.
